[57] CLAIM

The ornamental design for a refrigerator latch, as shown and described.

DESCRIPTION

FIG. 1 is a top, front, and left side elevational view of a refrigerator latch showing my new design, the broken-line disclosure of a refrigerator being for illustrative purposes only and forming no part of the claimed design;

FIG. 2 is an enlarged top, front, and left side perspective view thereof;

FIG. 3 is an enlarged right side elevational view thereof;

FIG. 4 is an enlarged left side elevational view thereof;

FIG. 5 is an enlarged bottom plan view thereof, the top being a mirror image of that shown; and

FIG. 6 is an enlarged rear elevational view thereof.
